UNITED STATES PATENT OFFICE.

WILLIAM J. O'LEARY, OF MONTREAL, QUEBEC, CANADA.

DRIVING UNIT FOR PHONOGRAHS OR THE LIKE.

Application filed August 5, 1924. Serial No. 730,306.

This invention relates to driving units, and particularly to a driving unit having a construction which particularly adapts it for actuating the record table of a phonograph 5 sound recording machine, or the like.

In the construction of phonographs and sound recording machines it is desirable to mount the driving mechanism directly beneath the record table to produce a compact 10 construction; and heretofore in the art the driving mechanism has generally been so mounted that there is rigid connection between the driving unit and the record table, thus permitting undesired vibrations to be 15 readily transmitted from the driving unit to the record and tone arm. With a driving unit which sets up relatively little vibration, such as the familiar spring motors or electric motors of the rotating armature type, 20 this construction is fairly satisfactory, though the vibrations transmitted from the driving unit interfere somewhat with the recording or reproducing operation. Vibration motors such as disclosed in the United 25 States patent to McDonald, 1,396,334 of November 8, 1921, are much less expensive to manufacture than the familiar types of rotating armature electric motors, and hence by their utilization driving units for phonographs, sound recording machines, and the 30 like may be provided which have the usual advantages of an electric drive, while being much less expensive than those heretofore in use. However, motors of this type set up 35 considerable vibration, and hence the usual motor mountings when used with this type of motor transmit so much vibration to the record and tone arm that the operation obtained is not as satisfactory as when spring 40 motors or electric motors of the rotating armature type are employed.

The principal object of the present invention is to provide a driving unit in which the motor mechanism is so mounted that the 45 apparatus with which the driving unit is employed is effectually shielded from motor vibrations.

Another object is to provide a substantially noiseless driving unit.

An important object of the present invention is to provide a motor construction which facilitates economical and effective lubrication of all bearings etc., even though the motor is completely enclosed.

Among the specific objects of the invention is the provision of an inexpensive driv-

ing unit suitable for actuating phonographs, sound recording apparatus, and the like.

In accordance with the above and other objects of the invention, an electric motor, 60 preferably of the vibration type, is suspended from an intermediate supporting member, in the form of an enclosing casing, by coil springs having a relatively high natural period of vibration. The enclosing casing is 65 in turn adapted to be suspended directly beneath the record table of a phonograph or the like by opposed coil springs having a relatively low natural period of vibration. This gives a construction in which the only 70 vibrations that are transmitted with substantial strength from the motor to the intermediate supporting member are of such a frequency that they will not be transmitted by the springs supporting the intermediate 75 supporting member. This intermediate supporting member being in the form of an enclosing casing the sound of the motor is effectually confined and is not transmitted to the outer air.

A vertical shaft for connection to a record table is journaled by a bearing secured in the top wall of the enclosing casing and is operatively connected with the motor solely by means of a felt coupling member, thus preventing vibrations from being transmitted from the motor to the shaft. An annular lubricant receiving cup embraces the shaft where it emerges from the enclosing casing, and all parts of the motor which require lubrication are aligned vertically beneath this cup, thus permitting them all to be lubricated by lubricant descending by gravity from the cup.

Figure 1 of the drawings is a longitudinal 95 vertical sectional view showing a phonograph driving unit embodying the present invention.

Figure 2 is a horizontal sectional view taken on the line 2-2 of Fig. 1 with the record table omitted.

Figure 3 is a transverse vertical sectional view taken on the line 3-3 of Figure 1.

Figure 4 is a fragmentary perspective view showing a motor and enclosing casing 105 mounted in accordance with the present invention.

Referring to Figures 1, 2, and 3 of the drawings, a tuning fork 1 is arranged to be vibrated by an electromagnet 2 and to actuate a transmission band 3, thereby rotating pulley 4 mounted on hollow vertical stud

or shaft 5 which is threaded into base member 6. The uni-directional driving of a pulley by means of a transmission band actuated by a vibrating tuning fork is old in the art and, per se, forms no part of the present invention. The theory of operation of motors which incorporate such construction is discussed in U. S. Patent to O'Leary 1,323,250, Jan. 6, 1925, and in U. S. Patent to Ramsey 1,379,212, May 24, 1921. Seated against a gasket on the upper edge of pulley 4 is a flaring cup 7 held in place by screws which have their heads sunk in two flat arcuate metal pieces 9 positioned in the bottom of the cup. One of these screws is shown in Fig. 1 and is designated by numeral 8. Each of the metal pieces 9 has an upstanding end 10, shown in dotted lines in Fig. 1. The upstanding ends 10 are simply flat pieces of strap metal which project upwardly from the bottom of hollow cup 7 and lie in a plane which includes the axis of shaft 5. These ends are 180 degrees apart and are located in slots in a felt coupling member 11 positioned in cup 7. A vertical shaft 12 to which may be attached a record table 13 passes through the center of felt coupling 11 and has affixed thereto a member having depending portions 14 which engage in slots in the felt coupling, which slots are located midway between the slots occupied by the upstanding portions 10 that are rigidly associated with pulley 4.

The motor mechanism comprising the tuning fork 1 and pulley 4 is positioned within an enclosing casing consisting of an upper section 15 and a lower section 16, and is supported from the upper section solely by means of coil springs 17. This enclosing casing acts as intermediate supporting member, and is in turn supported by opposed coil springs 18 arranged as shown in Figs. 3 and 4. Springs 17 are small and have a natural period of vibration which is relatively high, while springs 18 are large and have a natural period of vibration which is relatively low. This gives a relationship whereby vibrations of a frequency which are transmitted with appreciable strength by springs 17 are not so transmitted by springs 18; and hence only certain vibrations are transmitted from the motor to the intermediate supporting member (the enclosing casing) and these particular vibrations are not capable of transmission with appreciable strength by springs 18.

The shaft 12 is journaled near its upper end in a bearing 19 secured in the upper section 15 of the enclosing casing, and is provided at its lower end with a thrust bearing 20 carried by a U-shaped member 21 depending from section 15 of the enclosing casing. Shaft 12, thus rotatably mounted has its lower end passing through, but spaced from stud 5 as shown in Fig. 3 and hence therean

is no rigid path for the transmission of vibrations from the motor mechanism to this shaft. This construction coupled with the spring mounting just described effectually shields the record table and other portions of the apparatus from vibrations of the motor mechanism.

Vertical shaft 12 carries a gear 22 meshing with a worm 23 which transmits motion to a fly-ball governor 24 of well known construction. As the speed of shaft 12 increases governor plate 25 moves to the left and frictionally engages an adjustable member 26 of material such as rawhide thereby regulating the speed of shaft 12.

An annular lubricant receiving cup 30 is formed adjacent the upper end of bearing 19 and is accessible by merely removing the record table 13. Liquid lubricant placed in this cup descends through bearing 19, runs onto gear 22 and worm 23, is collected by cup 7 and absorbed by felt coupling 11, from which it seeps through the bearing of pulley 4 and is caught by cup 31 which acts as a reservoir to keep at least a portion of the engaging surface between pulley 4 and stud 5 submerged in lubricant. A portion of the lubricant absorbed by coupling 11 runs directly down the lower portion of shaft 12 and lubricates the thrust bearing 20. It is seen that this construction facilitates economical and effective lubrication of all parts requiring lubrication without access being had to the interior of the enclosing casing and even without access being had to the compartment in which the driving unit is mounted.

The casing enclosing the motor mechanism is preferably made of a good heat conducting material such as aluminum in order to readily conduct heat developed by the motor; and to aid in absorption and radiation of the heat by the casing both its interior and exterior surfaces are finished in dull black.

It is realized that the present invention may be practiced in forms other than those herein disclosed and hence it is desired that this disclosure be considered as illustrative, and not in the limiting sense.

Having thus described my invention, what I claim is:

1. A phonograph driving unit comprising an enclosing casing, means to resiliently suspend said casing from a support, resilient supporting means within said casing, a vibration motor supported within said casing by said supporting means, a vertical shaft having one end within said casing, a record table supported on the other end of said shaft, and a vibration deadening coupling connecting said shaft with said vibration motor.

2. A phonograph driving unit comprising an enclosing casing, means to resiliently sus-

pend said casing from a support, resilient supporting means within said casing, a vibration motor supported within said casing by said supporting means, a vertical shaft 5 having its lower end within said casing, a thrust bearing for the lower end of said shaft, a record table attached to the upper end of said shaft, and a vibration deadening coupling connecting said shaft to said vibration motor.

3. A driving unit comprising an enclosing casing, said casing consisting of an upper section and a lower section; motor mechanism supported from said upper section; a 15 shaft having one end projecting through the upper section into said casing; a U-shaped member attached to said upper section; a thrust bearing for said shaft carried by said U-shaped member; and means operatively 20 connecting said shaft with said motor mechanism.

4. A driving unit comprising an enclosing casing consisting of an upper section and a lower section; motor mechanism resiliently 25 supported from said upper section, said motor mechanism comprising an annular rotating member; a hollow member forming a pivot for said rotating member; a shaft journaled in said upper section and having one 30 end extending into but spaced from said hollow member; and a vibration deadening coupling operatively connecting said shaft with said rotating member.

5. In a phonograph, an intermediate supporting member, resilient means for supporting said intermediate supporting member free from rigid contact therewith, a motor 35 resiliently supported from said intermediate supporting member also free from rigid contact therewith, a shaft adapted to rotate a record table, and a vibration deadening coupling operatively connecting said shaft with said motor.

6. In a phonograph, an intermediate supporting member, opposed spring means for supporting said intermediate supporting member free from rigid contact therewith, a motor, resilient means supporting said motor from said intermediate supporting 40 means also free from rigid contact therewith, a shaft adapted to rotate a record table, and a vibration deadening coupling operatively connecting said shaft with said motor.

55 7. In a phonograph, an intermediate supporting member, springs for supporting said intermediate supporting member, a motor, and springs supporting said motor from said intermediate supporting member, said motor supporting springs and said intermediate member supporting springs having different natural periods of vibration.

8. In a phonograph, an intermediate supporting member, springs for supporting said intermediate supporting member, a motor, 65 springs supporting said motor from said intermediate supporting member, said motor supporting springs and said intermediate member supporting springs having different natural periods of vibration, a shaft adapted 70 to rotate a record table, and a vibration deadening coupling operatively connecting said shaft with said motor.

9. In combination; a driving member; a driven member; a bearing for one of said members; and a lubricant retaining coupling connecting said driving and said driven members, said coupling being adapted to feed lubricant to said bearing.

10. In combination, a driving member, a 80 driven member, a bearing for one of said members, a coupling connecting said members, a cup embracing said coupling, and a passage leading from said cup to said bearing 85 to conduct lubricant thereto.

11. In combination, a driving member, a driven member, a bearing for one of said members, a coupling connecting said members, and positioned above said bearing, a 90 cup embracing said coupling, and a passage leading from said cup to said bearing to conduct lubricant thereto.

12. In combination, a vertical shaft; a pulley mounted on said shaft, said pulley having a vertical annular groove in its lower edge; and a cup concentric with said shaft, the sides of said cup extending into said groove whereby said cup is adapted to hold lubricant to submerge at least a portion of said shaft.

13. In combination, a motor mechanism; a casing enclosing said motor mechanism, a shaft adapted to be driven by said motor mechanism and extending to the exterior of said casing, and a liquid lubricant receptacle exterior to said casing, the bearings of said shaft and said motor mechanism being vertically aligned beneath said receptacle to receive lubricant descending by gravity from said receptacle.

14. A driving unit comprising an enclosing casing, a shaft projecting upwardly from the interior of said casing, motor mechanism within said casing operatively connected to said shaft, and a cup on top of said casing adapted to receive lubricant and discharge it adjacent said shaft, the bearings of said shaft and motor being aligned vertically beneath the point of discharge from said cup whereby lubricant deposited in said cup will descend by gravity and lubricate all of the bearings.

WILLIAM J. O'LEARY.
